UNITED STATES PATENT OFFICE.

JOSEPH S. ISIDOR, OF NEWARK, NEW JERSEY, ASSIGNEE TO THE R. NEUMANN
HARDWARE CO., A CORPORATION OF NEW JERSEY.

BAG-FRAME FASTENER.

1,099,444.

Specification of Letters Patent.

Patented June 9, 1914.

Application filed April 11, 1914. Serial No. 331,132.

To all whom it may concern:

Be it known that I, JOSEPH S. ISIDOR, a citizen of the United States, residing at Newark, in the county of Essex and State of New Jersey, have invented certain new and useful Improvements in Bag-Frame Fasteners; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 The present invention has reference, generally, to improvements in bag-fasteners or catches which are ordinarily employed with the hinged frame-sections of bags, suit-cases, and the like; and, the invention relates, more particularly, to that class of bag-frame fasteners comprising a main shell adapted to be secured upon one of the frame-sections of the bag-frame, and provided with a hinged bolt-carrying plate.

25 The present invention has for its principal object to provide a bag-frame fastener comprising a chambered shell or casing and a bolt-carrying operating plate hinged or pivoted to the said casing or shell, and the said plate or other parts of the bag-fastener being provided with means to prevent any lateral play of the said bolt-carrying operating plate with relation to the upper face of the said chambered shell or casing and the hinged or pivoted connection between the said bolt-carrying operating plate and the said chambered shell or casing.

35 The invention has for its further object to provide a bag-frame fastener of the general character hereinafter more particularly set forth, with a view of providing a bag-frame fastener of a neat and greatly enhanced appearance.

45 Other objects of the present invention not at this time more particularly enumerated will be evident from the following detailed description of the invention.

With the various objects of the invention in view, the said invention consists, primarily, in the novel bag-frame fastener hereinafter set forth; and, furthermore, the invention consists in such novel arrangements and combinations of parts, as well as in the details of the construction of the same, all of which will be more fully described in

the following specification, and then finally embodied in the clauses of the claims which are appended to and which form an essential part of this specification.

The invention is clearly illustrated in the accompanying drawings, in which:

Figure 1 is a plan or top view of a bag-frame fastener made according to and showing one embodiment of the principles of the present invention, the hinged bolt-carrying plate being represented in its closed relation to the main box or shell of the fastener. Fig. 2 is a side elevation of the bag-frame fastener; Fig. 3 is an end elevation of the same, looking in the direction of the arrow *x* in said Fig. 1; and Fig. 4 is a similar view of the fastener, looking in the same direction, but showing the hinged bolt-carrying plate in its raised relation to the upper face of the main box or shell of the bag-frame fastener. Fig. 5 is a top or plan view of the bag-frame fastener of a slightly modified form of construction; Fig. 6 is a similar view of the fastener represented in said Fig. 5, but showing the bolt-carrying plate in its raised relation to the upper face of the main box or shell of the said bag-frame fastener; and Fig. 7 is a transverse vertical section of the fastener, said section being taken on line 7-7 in said Fig. 5, looking in the direction of the arrow *y*. Fig. 8 is a longitudinal vertical section of another bag-frame fastener and its hinged bolt-carrying plate provided with another means for preventing any lateral play of the bolt-carrying plate at its hinge-connection with the main box or shell of the fastener; and Fig. 9 is a transverse vertical section of the same, said section being taken on line 9-9 in said Fig. 8, looking in the direction of the arrow *z*.

Similar characters of reference are employed in the said above described views, to indicate corresponding parts.

Referring now to the several figures of the drawings, the reference-character 1 indicates the top or face-plate, 2 the longitudinally extending side-members or walls, and 3 the laterally extending end-members or walls of the main box or shell of the bag-frame fastener, the same as will be seen from an inspection of the several figures of the drawings, providing a suitably chambered body in which is suitably arranged and suitably secured by means of a rivet 4, or otherwise, the usual bolt-carrying plate controlling

spring 5, formed with the elongated slotted portion 6. In its top or face-plate 1, the box or shell of the bag-frame fastener is formed with an elongated opening or slot, as 7, 5 which registers with the slot 6 of the spring 5, and the purpose of which is self-evident. The said top or face-plate 1 is also provided with a laterally extending opening 8, and contiguous to said opening 8 are hinge-lugs 10 or ears, as 9, in which is suitably mounted a pintle, as 10. Extending above this pintle is the pivot-portion 12 of the herein-above mentioned bolt-carrying plate 11, said pivot-portion being provided with the pivot-ears 15 or lugs 13 which are mounted upon the said pintle 10, and extending from the edge of said pivot-portion 12, and located between the said ears or lugs 13, is a suitably formed spring-engaging element, as 14, in slidable contact with the spring 5, for maintaining the said bolt-carrying plate 11 in its lower position upon the top or face-plate 1, or in its raised position when lifted by means of its finger-piece-like edge 15 which projects 20 beyond the one end of the box or shell of the bag-frame fastener. The said plate 11 is provided with usual bolt 16 projecting downwardly from its lower face, and into and through the respective slots 6 and 7. In order to prevent any lateral play of the said plate 11 upon the upper face of the top or face-plate 1, when the plate 11 is in its closed relation with the said top or face-plate 1, owing to any loose connection of the members of the hinge-joint, the said bolt-carrying plate 11 has its longitudinal marginal edge-portions 17 projecting beyond the outer faces of the longitudinally extending side-members or walls 3, said plate 11 being 30 formed along said longitudinal marginal edge-portions 17 with suitably formed downwardly extending rib-like retaining elements or members, as 18, of any desired configuration, said elements or members 18 extending sufficiently down the said side-members or walls 3, as shown more particularly in Figs. 2 and 3 of the drawings, thus enhancing a portion of the main box or shell and consequently preventing any lateral motion or objectionable "wabble" of the said plate 11 upon the face-plate 1 when in its closed position.

Referring now to Figs. 5, 6 and 7 of the drawings, it will be seen, that by sufficiently narrowing the part 19 of the box or shell of the bag-frame fastener, the bolt-carrying plate 11 may be made of the same width as the part 20 of the box or shell, (see Fig. 5,) the marginal and downwardly extending 50 rib-like retaining elements or members 18, when the plate 11 is closed down embracing the narrower part 19 of the box or shell, in the manner illustrated in Fig. 7 of the draw-

ings, and thereby serving in the manner hereinbefore stated, to prevent any motion 65 or "wabble" of the plate 11 sidewise upon the main body or shell of the bag-frame fastener, as will be clearly evident.

If desired, the rib-like retaining elements or members 18 of the bolt-carrying plate 70 may be entirely omitted, and a flat plate 21 shown in Figs. 8 and 9 of the drawings may be used, and to prevent lateral movement or "wabble" of the said plate 21, the latter is provided with a downwardly extending stud, 75 post, or other suitable retaining member, as 22, which is adapted to enter a suitable opening or perforation, as 23, in the face-plate or top of the main box or shell of the bag-frame fastener, all of which will be understood 80 from an inspection of said Figs. 8 and 9 of the drawings.

The manipulation and operation of the parts will be clearly understood from an inspection of the several figures of the drawings and from the foregoing description of the same, and need not, therefore, be further described.

Of course, I am fully aware, that some changes may be made in the general arrangements and combinations of the several parts, as well as in the details of the construction of the said parts, without departing from the scope of the present invention as set forth in the foregoing specification and as 95 defined in the clauses of the claims which are appended to the said specification. Hence, I do not limit myself to the exact arrangements and combinations of the several parts as described in the said specification, nor do 100 I confine myself to the exact details of the construction of the said parts as illustrated in the accompanying drawings.

I claim:

1. A bag-frame fastener comprising a 105 chambered shell, a bolt-carrying plate hinged upon the upper face of said shell, and means connected with said plate and adapted to be brought into retaining engagement with a portion of said shell to prevent 110 lateral motion of said bolt-carrying plate.

2. A bag-frame fastener comprising a chambered shell, a bolt-carrying plate hinged upon the upper face of said shell, said bolt-carrying plate being provided with 115 rib-like members adapted to extend down the sides of said shell and embrace the same to prevent lateral motion of said bolt-carrying plate.

In testimony, that I claim the invention 120 set forth above I have hereunto set my hand this 9th day of April, 1914.

JOSEPH S. ISIDOR.
